UNITED STATES PATENT OFFICE.

SAMUEL DIGGLE, OF BRIXTON, LONDON, ENGLAND.

PROPELLER AND TRACTOR FOR USE IN AERIAL OR MARINE PROPULSION OR TRACTION.

1,246,891.

Specification of Letters Patent. Patented Nov. 20, 1917.

Application filed March 28, 1917. Serial No. 158,071.

To all whom it may concern:

Be it known that I, SAMUEL DIGGLE, a subject of the King of Great Britain and Ireland, and resident of Brixton, county of London, England, have invented a certain new and useful Improvement in Propellers and Tractors for Use in Aerial or Marine Propulsion or Traction, of which the following is a specification.

10 This invention relates in general to propellers, and more particularly to a novel improvement in blade construction especially adapted for use in propellers or tractors of the type employed in connection with aerial planes. It has been found desirable to make blades for propellers and tractors in such a manner that they may be readily assembled, repaired, adjusted and renewed in an expeditious manner, and without the aid of special tools or machinery. In making aerial flights it often happens that a propeller or tractor blade becomes damaged and the machine is forced to descend to make repairs, 25 and, being away from base it is desirable to carry blade parts which may be readily put together when the occasion demands to provide an entirely new blade or quickly repair the damaged one. That is to say, the invention proposes to provide a construction wherein every separate part of the propeller or tractor may be standardized and interchangeable, so that in the event of damage to one member of the same, that member can be speedily replaced, in contradistinction 30 to the fact that under present methods, should one part become damaged, the entire propeller is worthless. Further, a spare propeller can be carried in section in actual flight, thus enabling a pilot to replace either a part, or even the whole expeditiously and without special skill or tools.

Accordingly, with the foregoing general object in view it is proposed to provide a blade structure which involves an interior skeleton frame work which may be fitted with a suitable covering to form the blade proper. In other words, it is proposed to construct a blade having a suitable interior reinforcement which will not only provide the necessary foundation on which the complete blade may be built, but will also cause the blade to return to its normal position when it has been removed from torsion arising either through ordinary or abnormal load. Thus, an interior frame work is con-

templated which is flexible, strong and of sufficient stability to not only give adequate resistance to the blade when in use, but also bring the same back to the original position 60 when the blade is relieved from torsion or load, thus preventing so-called "tiredness" or "fatigue".

A further object of the invention is to provide novel means for attaching the blades 65 to the propeller hub, whereby the pitch of the blades may be readily adjusted or varied to meet various conditions of service and use.

With the above and other objects in view which will more readily appear as the nature 70 of the invention is better understood the same consists in the novel construction, combination and arrangement of parts herein-after more fully described, illustrated and claimed.

A preferred and practical embodiment of the invention is illustrated in the accompanying drawings, wherein:

Figure 1 is a vertical sectional view showing the skeleton frame work of the blade 80 which is intended to be surrounded by a suitable body, not shown.

Fig. 2 is a transverse section on the line 2-2 of Fig. 1.

Fig. 3 is a detail elevation on a smaller 85 scale of the web of the H-girder showing the taper thereof from the base toward the upper end.

Fig. 4 is an elevation partly in section showing a modified form of girder having 90 thereon the transverse webs which assist in forming the shape of the blades.

Fig. 5 is a transverse section on the line 5-5 of Fig. 4.

Fig. 6 is a detail perspective view of a 95 portion of a hub of a propeller wheel having thereon an adjustable blade carrying plate whose position may be altered to vary the pitch of the blades.

Similar references designate corresponding 100 parts throughout the several figures of the drawings.

In carrying the present invention into effect it is proposed to provide a main girder disposed longitudinally of the blade which 105 forms what may be termed the vertebra or backbone thereof since it has associated therewith suitable transverse webs or fins shaped to coincide with the section of the blade at the several points where they are 110 affixed, and of requisite strength to impart in conjunction with the other members of

the blade, such resistance as the particular blade in which they are employed may require.

Referring now to this longitudinally disposed reinforcing element of the blade it will be observed from Figs. 1 and 2 that the same is in the form of an H-girder consisting of three lengths of spring steel, namely a web member A of graduated height and the flange elements B. By reference to Fig. 3 it will be seen that the opposite edge portions of the tapering web A are provided with a plurality of offset tongues A', which are adapted to interlock with the opposite flange elements B of the beam, and in order to make this interlock possible, each of said elements B is provided with a plurality of slots B' for receiving the said tongues A' whereby when the said flange elements B are assembled on the web A, the tongue portions A' may be upset after the manner of riveting to hold the flanges to the web. A beam or girder thus formed, will be tapered or graduated longitudinally so that its tip end is smaller than its base end, and for the purpose of making the entire structure stable, and capable of facile assembly, it is proposed to provide a novel way for fitting the transverse ribs or web elements to the girder and securing the same in place.

These web elements are designated generally as F, and as previously indicated, are of a shape corresponding to the shape of the blade at the several points along the girder at which they are to be finally affixed, while their central portion is provided with a suitable opening or slot G corresponding in shape to the cross sectional character of the beam or girder, and of such size as to fit the beam at predetermined points. That is to say, the several transversely disposed webs F are provided with central openings of graduated size, the size of each corresponding to the portion of the beam where the web is to be finally anchored. With this formation of the webs it will be clear that the same are slidably fitted over and onto the beam until the size of the opening or slot therein coincides with the size of the beam, then the web will become wedgingly interlocked therewith and remain stationary. For instance, the web F which is nearest the base of the girder or beam will have a larger opening than the web which becomes anchored at the intermediate portion of the beam, and likewise the beam nearest the tip will have a smaller opening than the last mentioned web. Thus, the web having the largest opening must be slipped into place first, and the webs having smaller openings subsequently fitted over the beam in proper order. The application of the webs to the beam in this manner has the advantage of maintaining the built up girder in its assembled relation, and at the same

time locks the webs in such a manner that the so-called flexible characteristics of the entire blade skeleton, which permits the blade to assume its normal condition after the load is removed therefrom, is conserved. After the webs are thus assembled on the beam, it is proposed for the sake of additional bracing, to secure a tube, metal wire or its equivalent J through suitable countersunk notches K in the edges of the webs, so that while the rods will act as a support for the blade forming material, they will not project beyond the lines of the webs in the finished blade. In assembling the interior skeleton structure it may be noted that the H-beam is only partially assembled initially in order to permit the sliding of the transverse webs into place. That is to say, the ends of the flange members B adjacent the large end of the web A are made secure while the tip ends are left free to permit the web nearest the base being slipped in place, for if the parts B were secured to A throughout it would be impossible to slip the web having a slot corresponding in size to the cross section of the base, over the relatively small end of the beam. Therefore, it will be understood that the members B are only made fast to A after each web has been pushed into place. The taper of the H-beam when finally assembled holds the webs in place, without any other means since it will be clear that each web cannot move closer to the base on account of the size of its central slot, and likewise cannot be moved nearer the tip because the narrowing space between the flanges B-B will prevent any movement in this direction.

Referring now further to the girder shown in Figs. 1 to 3 inclusive, it may be noted that the lower end thereof is preferably flared outwardly in such a manner as to be capable of fitting within a suitable dovetailed socket designated generally as T formed in a carrier plate P adapted to be adjustably carried by the hub Q of the propeller. As shown in Fig. 7, this carrier plate P, having on its upper face the dovetailed socket T, has its lower face provided with suitable serrations V adapted to be engaged with complementary serrations V' or their equivalent for producing the required frictional engagement of the parts when the carrier plate is locked to the hub. The face of the hub Q having thereon the serrations V' has associated therewith suitable upstanding bolts Y which are adapted to pass through elongated openings Z in the carrier plate P which permit of the latter being adjusted with reference to the hub Q when the nuts W are loosened, while on the other hand when the said nuts W are made tight on the threaded bolts Y the carrier plate is rigidly clamped to the hub. The dovetailed socket T formed on the upper

face of the carrier plate is accessible from one end, while the opposite end is closed as indicated at T' and for the purpose of locking the blade therein, the opposite parallel walls T² of the plate which form the sides of the socket are provided with suitable openings to receive the transverse holding and locking bolts U which preferably have the heads U' at one end and the securing bolts U² at the other.

From the foregoing it will be understood that the carrier plate P provides for securely fastening the flared lower end or base of the blade in the dove-tailed socket T, and securely locking the same therein by the bolts U. When the blade is adjusted on the carrier plate to the proper pitch, the latter is locked to the hub Q by the nuts W on the bolts Y being screwed downwardly to cause the two serrated faces V and V' to engage and firmly hold the blade stationary.

A modified form of girder is shown in Fig. 4 of the drawings. Instead of making this girder of the H form shown in Figs. 1, 2 and 3 of the drawings, it is proposed to embody all of the same characteristics in different structural form. That is to say, it is proposed to utilize a plurality of flat spring strips or slats C, in the present instance, of suitable length and thickness, which are held suitable distances apart by means of graduated spacing sleeves E and fastening bolts E'. As shown the two outer strips C—C in Fig. 4 taper toward the tip end of the central strip, thus producing a girder of graduated or tapering formation whose base is considerably wider than this tip, thus facilitating the application of the transverse webs F', which are applied in the same manner as the webs F in Fig. 1. However, these webs are provided with slots G' which of course correspond with the cross sectional shape of the beam as shown in Fig. 5 of the drawings. The lower ends of the strips C—C—C have fitted therebetween suitable filler blocks S—S which add to the strength of the base of the girder and insure a tight and accurate fit in the socket T of the carrier plate P heretofore referred to. Thus, it will be clear that the modification shown in Fig. 4 embodies all of the essential characteristics of the girder shown in Fig. 1, since it is of tapering or graduated size, has the transverse web members telescopically fitted thereover, and has the flared base portion adapted to fit within the dove-tailed socket T.

Without further description it is thought that the structural features and characteristics will be apparent, and with further reference to the features and advantages thereof it may be noted that the present invention makes possible the designing of the various sections, angles, and curvature of the

blades to conform with accurate predetermined standards, and true efficiency. Furthermore, the novel arrangement of girders and web members takes care of the varying pressures on the blades so that when an abnormal load is placed on the blade it will be effectually resisted and afterward the blade will automatically assume its original place and position. In other words, greater resisting power and uniformity is the invariable result of using steel instead of wood, while at the same time giving greater accuracy, standardizing production, obviating the warping and dissolution tendencies of wood and glue construction, and facilitating packing and transport. Also, in the present construction a true streamline cone of entry is effected, and the maximum translation speed of the engine is conveyed into efficient dynamic thrust, while at the same time the provision of means for altering the angle of adjustment of the blade to provide different pitch, is of great value when the venue of flight is changed from one atmospheric condition to another.

I claim:

1. In a propeller or tractor construction, a blade having interior reinforcement, the said reinforcement including a longitudinal stiffening member of graduated areas in cross section and transverse members having locking telescopic engagements therewith at spaced intervals.

2. In a propeller or tractor construction, a blade having interior reinforcement, said reinforcement consisting of a centrally located reinforcing girder of graduated areas in cross section, and transverse members each having a central opening corresponding in shape to the cross section of the girder and of graduated sizes to register with the dimensions of the girder at predetermined spaced intervals.

3. In a propeller or tractor construction, a blade having interior reinforcement, said reinforcement including a longitudinal stiffening member tapering toward the end of the blade, transverse web members each having a central opening for telescopically fitting over the stiffening member and adapted to wedge thereon at spaced intervals, and a reinforcing member carried by said web members.

4. In a propeller or tractor construction, a blade having interior reinforcement, said reinforcement comprising a longitudinally disposed flanged beam, transverse web members having a telescopic fit over said beam, and a reinforcing member carried by said web members.

5. In a propeller or tractor construction, a blade having interior reinforcement, said reinforcement comprising a longitudinally disposed H-beam progressively diminishing in size toward its outer end, transverse web

members having a central opening corresponding to the shape of said beam and of a size corresponding to predetermined points thereof, whereby said web members may have a locking telescopic engagement with the beam, and a reinforcing element carried by the said web members.

6. In a propeller or tractor construction, a blade having interior reinforcement including a central stiffening member having a tapered base, a hub, a carrier plate having a dove-tailed socket for receiving the base of the stiffening member, and means for effecting the adjustment of the carrier plate 15 on the hub.

7. In a propeller or tractor construction, the combination of a hub having an adjustment face thereon, a blade carrier having means for adjustably engaging the said

adjustment face of the hub, means for locking the carrier to the hub to hold the same in an adjusted position, a holding socket formed on the carrier plate for receiving the blade, and locking means associated with said holding socket for detachably locking 25 the blade therein.

8. In a propeller or tractor construction, a blade having interior reinforcement, said reinforcement consisting of a built up tapering girder, and a plurality of transverse 30 web elements having a frictional telescopic engagement therewith.

In testimony whereof I have affixed my signature hereto this 6th day of March, 1917.

SAMUEL DIGGLE.
